M. MITCHELL.
WIRE STRETCHING AND TWISTING DEVICE.
APPLICATION FILED MAR. 24, 1919.

Patented Mar. 22, 1921.

Inventor
Moorehouse Mitchell

By
William Clinton

Attorney

UNITED STATES PATENT OFFICE.

MOOREHOUSE MITCHELL, OF QUEBEC, QUEBEC, CANADA.

WIRE STRETCHING AND TWISTING DEVICE.

1,372,531.

Specification of Letters Patent. Patented Mar. 22, 1921.

Application filed March 24, 1919. Serial No. 284,817.

To all whom it may concern:

Be it known that I, MOOREHOUSE MITCHELL, a subject of the King of Great Britain, residing at Quebec, Province of Quebec, Canada, 5 have invented certain new and useful Improvements in Wire Stretching and Twisting Devices; and I do hereby declare that the following is a full, clear, and exact description of the invention, such as will enable 10 others skilled in the art to which it appertains to make and use the same.

The present invention relates to devices for stretching wires and twisting the ends thereof whereby connecting loops may be 15 formed.

An object of the present invention is to provide a device of the character aforesaid, whereby the ends of wires may be easily and readily gripped so that they may be stretched 20 and when so gripped connecting loops may be formed at the end of the wires.

With the above and other objects in view which will hereinafter appear as the description continues, the invention consists of the 25 novel features of construction, combination and formation of parts as will be hereinafter more fully described and particularly pointed out in the appended claim.

In the accompanying drawings has been 30 shown a simple and preferred form of the invention, it being, however, understood that no limitation is necessarily made to the precise structural details herein exhibited, but the right is hereby reserved to any changes, 35 alterations or modifications to which recourse may be had that come within the scope of the claim without departing from the spirit of the invention or sacrificing the efficiency of the same.

40 In the accompanying drawings:

Figure 1 is a side elevation of the device embodying the present invention;

Fig. 2 is a plan view of the same;

Fig. 3 is an enlarged detail section;

45 Fig. 4 is an enlarged detail section taken at right angles to Fig. 3; and,

Fig. 5 is a detail view of one of the gripping jaws.

Referring now more particularly to the accompanying drawings wherein like and corresponding parts are designated by similar reference characters throughout the several views.

The device comprises a suitable stand or 55 support 1 having pivotally mounted therein as at 2 a lever 3 and one end of this lever 3

is provided with a handle 4. The opposite end of this lever is provided with a pair of extension plates 5 between which is pivotally mounted as at 6 a band 8 and this latter is seated within a groove formed in the outer periphery of a sleeve 7. A bolt 9 connects the opposite end of this band 8 so as to grip the sleeve 7 or permit the sleeve to revolve freely within the band 8. The gripping device comprises a pair of jaws 10 which when connected form substantially a cone-shaped block which may be seated within the sleeve 7. The upper ends of these jaws 10 are secured within a sleeve 11 by means of a bolt 12 and a suitable washer 13 encircles this bolt 12 and is arranged between the jaws.

There is sufficient play between the upper ends of the jaws and inner sides of the cap to permit the jaws to slide slightly upon the 75 pin 14.

The pin 14 extends through the jaws 10 and a lever 15 is pivotally connected thereto. Arranged between the jaws is a coil spring 16 which normally holds the jaws in spaced 80 relation and the lower inner faces of these jaws are milled as at 17 so as to provide gripping faces. The lower ends of these jaws are each provided with an enlarged portion forming an annular rim 18. When 85 the jaws 10 have been forced together so as to compress the spring 16 they may be seated within the sleeve 7 as the rim 18 will be permitted to pass through the sleeve 7. When the jaws have been seated within the sleeve 90 the pressure may be released and the spring 16 will cause the jaws to be expanded whereby their outer periphery will frictionally engage the inner periphery of the sleeve 7.

In stretching a wire 19 the device may be seated upon a suitable support 20 and one end of the wire will be placed between the gripping faces 17 of the jaws. By applying a force to the handle 4 of the lever 3 in a downward direction the sleeve 7 will be 95 caused to slide upon the outer cone faces of the jaws 10, whereby the jaws will securely grip the wire and the greater the pull upon the wire the tighter the jaws will grip the same. When it is desired to form a loop or twist the ends of the wire 19, the jaws may be revolved by turning the handle 15 and as the sleeve 7 is loosely mounted within the band 8 the jaws and sleeve may be revolved when performing the twisting operation.

Having thus fully described my invention,

what I claim as new and desire to secure by Letters Patent is:

In a device of the character described, a support, a lever pivoted in said support, 5 plates forming a fork secured to one end of said lever, a band pivotally connected in said fork end of the lever, said band having its ends adjustably connected, a sleeve having a groove in its outer side attached to the lever by said band, for rotation relative to the lever, a tapered block arranged within said sleeve and movable vertically therein, said

tapered block comprising a pair of gripping jaws movable to and from each other, a spring normally holding said jaws apart, 15 and a lever pivotally connected to said block, substantially as and for the purposes set forth.

In witness whereof I have hereunto set my hand.

MOOREHOUSE MITCHELL.
